UNITED STATES PATENT OFFICE.

THOMAS MATTHEWS, OF BROOKLYN, NEW YORK.

LIFE-SAVING SUIT.

1,082,643.

Specification of Letters Patent. Patented Dec. 30, 1913.

Application filed October 25, 1912. Serial No. 727,655.

To all whom it may concern:

Be it known that I, THOMAS MATTHEWS, a citizen of the United States, and resident of Brooklyn, in the county of Kings and 5 State of New York, have invented certain new and useful Improvements in Life-Saving Suits, of which the following is a specification.

This invention relates to life saving devices and more especially to suits which are 10 made of waterproof material, so as to completely envelop the body and limbs of the wearer, in order to exclude the water, and to be lined with woolen or other heat confining 15 fabric, so that the individual using the suit may remain in freezing water for hours without freezing or experiencing any serious inconvenience.

These and other objects and details of the 20 invention will be more fully explained in the following specification, set forth in the claim, and illustrated in the drawings, wherein:

Figure 1 shows the suit on the wearer; 25 Fig. 2 is a view of the suit removed from the wearer; Fig. 3 is a cross sectional view of the suit at about the chest.

A very serious danger to persons thrown 30 into the water and especially during that part of the year when the water is near freezing temperature is that the individual, if not drowned, is apt to die from the cold, if not immediately removed from the water. This is often the case with 35 hunters using frail boats, or with passengers on ocean liners deficient in floating life saving appliances, and although the parties thrown into the water may have life belts, they are not protected from the killing tem- 40 perature.

The present invention is designed to overcome this difficulty by providing a water proof and water tight suit and lining it with a material which will prevent the coldness of the water from cooling the body of 45 the wearer. The suit will also be provided with corks or other buoyant means, especially around the chest to not only float the wearer but to retain him in an upright position in the water.

The suit is ordinarily made to closely fit the form of the wearer, completely incasing

the feet and legs and having a hood 5 for the head. The arms 6 may be open at their extremities and have flexible cuffs 7 to close 55 the space about the wrists and exclude the water, while pockets 8 are provided at the front, and also at the back, if necessary, for the slabs of cork 9 or other buoyant substances, or the suit may be provided with 60 a pneumatic belt, to be blown up after the suit is put on.

The front of the suit is provided with a placket at its front with eyelets along the edges to carry a lacing cord 10, by which the 65 placket may be closed and retained in that condition to complete the arrangement of the suit. Within the placket is a rubber sheeting 11 to prevent the entrance of water at that point. This practically excludes all 70 chance of water entrance except at the neck, where the fit may be tight enough to prevent the entrance of water at that point. The hands may be left uncovered, so that they may be employed to put on the suit 75 and close the placket and lace and tie the same.

The interior of the suit may be provided with a lining 12 of wool or other comfortable fabric to exclude the cold and retain 80 the heat of the body. Water tight closures may be adopted to exclude the water around the wrists and neck to prevent the lining from wetting and cooling the wearer. It is obvious that the suit may be otherwise 85 altered or modified without departing from the essential features above described.

What I claim as new and desire to secure by Letters Patent is:

In a life saving suit, the combination with 90 a water proof suit having a heat retaining lining and a placket, of lacing means at the placket, a filling piece at the placket, a hood integral with the suit and having similar lining, pockets at the chest of the suit, floats 95 for the pockets, and flexible cuffs.

Signed at New York in the county of New York and State of New York this 26th day of Sept., A. D. 1912.

THOMAS MATTHEWS.
